Primary Examiner — Clare E Heflin*(74) Attorney, Agent, or Firm* — Daniel J. Piotrowski**CLAIM**

The ornamental design for a high mast luminaire, as shown and described.

DESCRIPTION

FIG. 1 is a top perspective view of a high mast luminaire showing the new design;

FIG. 2 is a bottom perspective view thereof;

FIG. 3 is a top plan view thereof;

FIG. 4 is a bottom view thereof;

FIG. 5 is a left-side elevation view thereof;

FIG. 6 is a right-side elevation view thereof;

FIG. 7 is a front elevation view thereof; and,

FIG. 8 is a rear elevation view thereof.

The broken lines shown represent portions of the high mast luminaire that form no part of the claimed design.

The area between the pair of curved dashed lines forms no part of the claimed design.
